UNITED STATES PATENT OFFICE.

SILAS W. HOLBROOK, OF CATSKILL, NEW YORK.

IMPROVEMENT IN WASHING-MACHINES.

Specification forming part of Letters Patent No. 159,094, dated January 26, 1875; application filed November 21, 1874.

To all whom it may concern:

Be it known that I, SILAS W. HOLBROOK, of Catskill, in the county of Greene and State of New York, have invented a new and useful Improvement in Washing-Machine, of which the following is a specification:

Figure 1 is a vertical section of my improved machine, taken through the line *x x*, Fig. 2. Fig. 2 is a horizontal section of the same, taken through the line *y y*, Fig. 1.

Similar letters of reference indicate corresponding parts.

The invention is an improvement in the class of washing-machines distinguished by a vertical revolving ribbed cylinder and vertical ribbed or corrugated yielding plates or staves, forming part of the inner surface of the clothes-containing tub or box. The invention relates to the arrangement of the yielding plates forming the continuous inner wall of the suds-box, and being free to move at each end between parallel guide-blocks, as hereinafter described.

A represents the suds-box or tub, which may be made cylindrical or slightly tapering in form. *B* is a circle of staves or upright bars, the forward or inner sides of which are corrugated or ribbed longitudinally, and which are placed at a distance of two inches, more or less, from the sides of the tub *A*. The upright bars are held out to their places, and at the same time are allowed to yield to accommodate themselves to the varying thickness of the clothes being washed, by springs *C*, interposed between them and the sides of the tub *A*. The bars or staves *B* are made to move out and in radially by guide-blocks *D*, interposed between their ends, or between tenons formed upon their ends. The lower set of guide-blocks *D* is secured to the bottom or to the sides of the tub *A*, and the upper set of guide-blocks *D* is secured to the sides of the said tub *A*. The bars or uprights *B* are kept from moving so far inward as to get out of place by hoops *E*, attached to the

inner ends of the guide-blocks *D*. *F* is a cylinder, seven inches, more or less, in diameter, the lower end of which is pivoted to the center of the bottom of the tub *A*, and to its upper end is attached a shaft, *G*, which passes out through a hole in the cover *H*, and to its upper end is attached a bevel-gear wheel, *I*, into the teeth of which mesh the teeth of a bevel-gear wheel, *J*, attached to the inner end of the shaft *K*. The shaft *K* revolves in bearings *L*, attached to the cover *H* and tub *A*, and to its outer end is attached a crank, *M*, by means of which the machine is operated. The cover *H* is made in two parts, the larger part, through which the shaft *G* passes, being permanently attached to the tub *A*. To the sides of the cylinder *F* are attached ribs or wings *N*, to take hold of the clothes and carry them around as the said cylinder *F* is rotated. The lower hoop, *E*, is beveled off upon its inner side, and the lower end of the cylinder *F* is surrounded with a beveled ring, *O*. This construction prevents the clothes from getting in beneath the lower ends of the uprights *B* and cylinder *F*, and being worn or cut. The clothes to be washed are put into the space between the ribbed spring uprights *B* and the ribbed cylinder *F*, and are carried around through said space by the revolution of the said cylinder, and are washed clean in a very short time by being rubbed against the uprights *B*, and by being carried around through the water.

Having thus described my invention, I claim as new and desire to secure by Letters Patent—

The combination of the vertical ribbed plates *E*, guide-blocks *D*, and springs *C*, said plates being arranged to form the inner wall or side of the suds-box, and to yield or move outward at either end, as shown and described.

SILAS W. HOLBROOK.
